UNITED STATES PATENT OFFICE.

CHARLES DENNISTON BURNLEY, OF KILMESTON, ALVESFORD, ENGLAND.

AERONAUTICAL APPARATUS

1,071,140.

Specification of Letters Patent.

Patented Aug. 26, 1913.

Application filed January 25, 1913. Serial No. 744,172

To all whom it may concern:

Be it known that I, CHARLES DENNISTON BURNLEY, a subject of the King of Great Britain and Ireland, residing at Dean 5 Holme, Kilmeston, Alvesford, in the county of Hants, England, have invented new and useful Improvements in and in Connection with Aeronautical Apparatus, of which the following is a specification.

10 This invention relates to improvements in aeronautical apparatus and has for its object to enable the same to alight upon or ascend from water with increased safety and reliability, while at the same time obviating the risk of pique or pitching which is involved when, in alighting, the lower part of the apparatus is abruptly retarded owing to its becoming immersed.

In the specification which accompanied 20 my Patent Application Ser. No. 736,836 filed on the 14th December, 1912, is described a hydro-aeronautical machine wherein the fuselage consists of a water-tight boat-like structure beneath which are arranged 25 hydropeds furnished with numerous hydroplanes, the latter being arranged in step formation; that is to say, in superposed horizontal planes.

In the accompanying drawings Figure 30 1 is a side elevation, Fig. 2 a front elevation, and Fig. 3 is a broken plan view of a hydro-aeronautical machine embodying my present improvements. As will be seen, the hydropeds A are arranged obliquely with 35 considerable lateral rake, with the effect that the lifting force, produced by the hydroplanes a carried by either of the hydropeds, is transmitted directly to the fuselage or body portion B, through the hydroped concerned. The hydropeds A are, however, utilized to furnish low points of attachment for the under-ties C, whereby the wings of an apparatus of the heavier-than-air type are held against upward collapse. 40 By providing such low points of attachment for the said under-ties, the employment of supporting surfaces of increased span is rendered practicable, with a consequent gain in the efficiency of the apparatus. The said 45 hydropeds are also connected together by

means of cross-ties a' and thus afford one another mutual support.

Adjacent to the lowermost hydroplanes are arranged one or more propellers D, adapted for use in water and capable of being driven from the main engine employed for driving the aerial propeller. As the apparatus, under the influence of the propellers D or the aerial propeller or propellers or of both sets collectively, gather speed, it rises by degrees and finally its whole weight becomes transferred from the hydroplanes to the aeroplanes, as the machine is launched in flight. Before again alighting upon water, the water-propellers 55 D are set in motion with the effect that the lower portion of the apparatus is maintained well in advance and the risk of "pique" is obviated.

In a machine of the character herein referred to, it has been found that, if the wing warping control-connections be led by way of the hydropeds, so that they are immersed in water, they occasion considerable head-resistance, and are moreover liable to 75 injury from contact with floating bodies. In Fig. 3 is illustrated in plan my improved method of effecting the wing-warping and of arranging the control-connections, whereby these disadvantages are obviated.

Upon the wing H is mounted a longitudinal overhead spar h supported upon converging struts and ties h' which are suitably trussed. To one or more points in the overhead spar are connected the wing-warping control-connections h², which are then led rearwardly in relation to the machine, inwardly through the after portion of the fuselage B and forwardly to the usual control levers or wheels. The overhead spar 85 h may be connected with its struts and ties h', and through them with the wing H, in such a manner as to permit of the structure, when not in use, being collapsed or folded together.

When it is desired to warp one of the wings, a rearward pull is transmitted through the control-connections to the overhead spar pertaining to that wing and exerts a torsional effect on the latter.

I claim:—

In a hydro-aeronautical machine, the
herein described means for use in warping
the supporting surfaces or wings, same
comprising a longitudinal warping spar,
mounted above the wing, in conjunction
with control-connections leading from the

control lever or wheel to the warping spar
and arranged entirely above the water level.

CHARLES DENNISTON BURNEY.
